(57) **CLAIM**

The ornamental design for an insulated container with removable lid, as shown and described.

DESCRIPTION

FIG. 1 is a front perspective view of an insulated container with removable lid, showing our new design;

FIG. 2 is a front perspective view thereof, shown with the lid removed for clarity of the disclosure;

FIG. 3 is a front view thereof, the rear and side views being identical;

FIG. 4 is a front view thereof, shown with the lid removed for clarity of the disclosure, the rear and side views being identical;

FIG. 5 is a top view thereof;

FIG. 6 is a top view thereof, shown with the lid removed for clarity of the disclosure;

FIG. 7 is a bottom view thereof;

FIG. 8 is a bottom view thereof, shown with the lid removed for clarity of the disclosure;

FIG. 9 is a front perspective view thereof, shown with the container removed for clarity of the disclosure;

FIG. 10 is a top view thereof, shown with the container removed for clarity of the disclosure;

FIG. 11 is a front view thereof, shown with the container removed for clarity of the disclosure, the rear and side views being identical;

FIG. 12 is a bottom view thereof, shown with the container removed for clarity of the disclosure;

FIG. 13 is a front perspective view thereof, shown in environmental use; and,

FIG. 14 is a front perspective view thereof, shown in environmental use, the rear and side views being identical. The broken lines in FIG. 6 illustrate the portions of the insulated container with removable lid that form no part of the claimed design.

The broken lines in FIGS. 13 and 14 depict environmental subject matter only and form no part of the claimed design.

1 Claim, 14 Drawing Sheets
